UNITED STATES PATENT OFFICE.

ELIZABETH F. McCARTNEY, OF OMAHA, NEBRASKA.

SEWING-THIMBLE.

SPECIFICATION forming part of Letters Patent No. 293,262, dated February 12, 1884.

Application filed September 3, 1883. (No model.)

To all whom it may concern:

Be it known that I, ELIZABETH F. McCARTNEY, of Omaha, Douglas county, in the State of Nebraska, have invented certain new and useful Improvements in Sewing-Thimbles, of which the following is a specification.

The object of the invention is to more effectually relieve the root of the finger-nail from pressure, and to support the thimble in position by a sufficient bearing above and below, and also to ventilate the space thus provided, while thoroughly protecting it.

The invention avoids the irritation due to pressure on the finger at and immediately adjacent to the base or root of the nail, and by sufficiently ventilating that portion of the thimble, avoids the tenderness and brittleness of the nail, which is sometimes experienced with long use of the ordinary unventilated thimbles.

The accompanying drawings form a part of this specification, and represent what I consider the best means of carrying out the invention.

Figure 1 is a side elevation; Fig. 2, a top view, and Fig. 3 a central longitudinal section. Fig. 4 is a side elevation, representing a modification.

Similar letters of reference indicate corresponding parts in all the figures.

A is the top or apex of the thimble; A', the portion of the side adjacent to the top; and A², the band or base—the portion of the thimble farthest from the top. A³ is an intermediate portion. This part A³ is of greater diameter than the adjacent portions on each side. It may, and preferably does, partake of the general conical form of the thimble. It may be made in one with the parts A', A², the metal of this part being simply forced out be-

yond the adjacent parts. It may, if preferred in any case, be made in a separate piece, and attached to the adjacent parts by brazing or otherwise. This part A³ is ventilated by holes a. These are profusely distributed over the entire area of the part A³, except the upper edge, and afford adequate ventilation. They are small and inclined, as shown. The needle will not, under any ordinary or extraordinary conditions, enter these perforations. In what I esteem the best form of the invention, this portion A³, of larger diameter than the adjacent parts, is extended uniformly quite around the thimble. This allows the thimble to be applied in any position, and is certain to properly relieve the root of the nail from pressure. A good portion of the advantages of the invention can, however, be secured by letting the raised portion A³ extend only half-way around, or even less. This latter construction is shown in Fig. 4.

I claim as my invention—

1. The sewing-thimble described, having a raised portion, A³, extended partially or entirely around, adapted to relieve the root of the finger-nail from pressure, as herein specified.

2. A thimble having a portion, A³, both raised and furnished with fine perforations a, adapted to relieve the nail from pressure, and to ventilate the space, while completely protecting it from the needle, as herein specified.

In testimony whereof I have hereunto set my hand, at New York city, this 30th day of August, 1883, in the presence of two subscribing witnesses.

ELIZABETH F. McCARTNEY.
